(57) **CLAIM**

The ornamental design for a carbonator, as shown and described.

DESCRIPTION

FIG. 1 is a front perspective view of a carbonator in an open position;

FIG. 2 is a back view of the carbonator of FIG. 1;

FIG. 3 is a bottom view of the carbonator of FIG. 1;

FIG. 4 is a front view of the carbonator of FIG. 1;

FIG. 5 is a left side view of the carbonator of FIG. 1;

FIG. 6 is a right-side view of the carbonator of FIG. 1;

FIG. 7 is a top view of the carbonator of FIG. 1;

FIG. 8 is a perspective view of the carbonator of FIG. 1 in the closed position;

FIG. 9 is a front perspective view of a second embodiment of a carbonator shown in an open position.

FIG. 10 is a back view of the carbonator of FIG. 9;

FIG. 11 is a front view of the carbonator of FIG. 9;

FIG. 12 is a left side view of the carbonator of FIG. 9;

FIG. 13 is a right-side view of the carbonator of FIG. 9;

FIG. 14 is a top view of the carbonator of FIG. 9; and,

FIG. 15 is a perspective view of the carbonator of FIG. 9 in a closed position.

The broken lines showing portions of the carbonator form no part of the claimed design.

1 Claim, 15 Drawing Sheets
